(57) CLAIM

The ornamental design for a product protector, as shown and described.

DESCRIPTION

FIG. 1 is a front isometric view of a first embodiment of a product protector, showing my design;

FIG. 2 is a rear isometric view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front isometric view of a second embodiment of a product protector;

FIG. 10 is a rear isometric view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken line showing of parts of the drawings is included for the purpose of illustrating portions of the product protector and forms no part of the claimed design.
